SIGN HOLDER

Theodore T. Stack, Chicago, Ill., assignor to Payne
Products Co., Barrington, Ill., a firm

Application June 23, 1939, Serial No. 280,739

4 Claims. (Cl. 40—140)

This invention relates in general to a double-faced sign and has more particular reference to a roadside, direction, or double-face sign in which letters, figures or other characters are interchangeably placed for easily varying the designation on the signs, for oppositely disposing the characters on the opposite faces of the sign to read correctly from both directions, and to provide means for quickly and firmly locking and holding different letters or characters in the sign with provisions for releasing or interchanging the letters or characters if desired.

Further objects of the invention are to provide means for suitably supporting a sign; to provide a jeweled reflector for aiding in locating the sign from a distance; and to provide a one-piece frame structure in which a plurality of letters or characters may be placed interchangeably and releasably locked in place so that they are not easily removed except by the application of a simple tool, in which case the letters or characters are easily loosened, inserted, removed and locked in place.

In the accompanying drawing illustrating a preferred embodiment of the invention,

Fig. 1 is a side elevation of a sign constructed in accordance with this invention;

Fig. 2 is a sectional view of the sign showing the structure and method of locking the letters or characters in place;

Fig. 3 is a sectional view similar to Fig. 2 showing a single reflector; and

Fig. 4 is an enlarged detail view as taken on the line 4—4 of Fig. 1 illustrating the application of a tool to deflect the bendable edge.

In displaying directional or house number signs at the roadside or adjacent to a house or other premises, it is desirable to provide a substantial supporting frame, preferably of metal, which will not be easily broken or disfigured and to which letters or characters may be easily applied, interchanged, and from which they may be removed without much trouble and without taking too much time, by someone having the proper tools, letters and characters for making the signs and changes therein.

In the present invention the objections are overcome by providing a supporting metal frame with a fixed flange at one side and a deflectable flange at the other side adapted to be offset or set over against the edges of letters or characters by a suitable and simple tool for tightening the letters or characters against the opposite flange and reversely for loosening the letters or characters when they are to be renewed or changed.

Referring now more particularly to the drawing, a frame 5 is made of suitable metal or other material to provide an outer supporting rim 6 having approximately rectangular dimensions with a central rectangular aperture 7 having a fixed flange 8 at one side set off around the edge by a groove 9 and having an opposite flange 10, the inner edge of which forms a continuation of the opening 7 with its outer edge formed by a groove 11.

At the top of the frame, preferably at the longitudinal center thereof is a rounded boss 12 for holding reflector buttons 13 at opposite sides thereof and these buttons may be colored so that when light from a headlight or a searchlight 15 shines thereon, the colored or other reflection will be visible for a long distance to aid in locating the sign.

At the lower edge of the frame is a recessed boss or projection 14 to receive a rod or support 20 15 for supporting the frame in raised or any other position, the frame being attached by a set screw 16 or any other suitable fastening device. If this frame is set up so that both sides are visible, from opposite directions, it will be necessary to reverse the letters or characters in the sign in order that the number or directions may be correctly read.

The frame herein shown is intended to receive four different characters longitudinally thereof and these characters each comprise an outer plate or mask 17 with an under or lower reflector 18. The reflector may be a single plate extending the full length of the frame with reflecting surfaces on both sides or separate pieces the same width as the character masks 17 may be provided; or separate thin plates 18 may be provided with outer reflecting surfaces placed oppositely between character plates 17 at opposite sides so that the same or different characters will be presented at opposite sides of the frame, the shape of the mask determining the letter or character which is shown, and the reflecting surface making the letter or character clearly visible in the daytime, and also at night when a light shines 45 thereon.

In first applying the letters or character to the frame, the opposite mask 17 and reflectors 18 are assembled in proper order and succession within the opening 7 of the frame abutting the fixed flange 8. When pressed together they are contained within the recess below the flange 10 which being relatively thin and of soft metal is easily offset, deflected or set over by a tool 20 in the nature of a flat chisel which is applied 55

to the groove 10 and pounded or tapped to deflect the flange inwardly, engaging and gripping the edges of the masks 17 and binding them tightly in the opening 7.

5 To release the letters or characters from the frame the same instrument 20 is applied to the inner or opening edge of the flange 10 which is pressed outwardly by a sharp tap or blow with a hammer all along at least one inner edge of the flange, thereby releasing the edges of the letter or character mask 17 and the reflectors 18.

10 If the letters and reflectors are made in sections, one section may be removed and replaced at a time, but if the reflector is of a single sheet 15 or plate for all the characters of a frame, then one entire edge of the flange 10 must be offset in order to release all of the letters, characters and plates therefrom. In practice, the bendable flanges 10 on both sides are preferably offset or 20 set over so that a minimum deflection of the metal from the groove 11 is necessary. This will permit a number of changes of the letters or characters in the frame without danger of breaking the bendable flange as this portion of the frame is usually made of soft metal or alloy containing lead or aluminum which will permit considerable deflection or offsetting without 25 breaking. In practice no actual bending or fracture of the metal is necessary as the letter plates 30 and reflectors fit closely within the opening of the frame and only a small deflection of the frame is necessary.

35 This frame may be reused for different locations or for different purposes, it being necessary only to change the letters or characters therein accordingly. Any desired sign or number combination is easily made up to order which makes it unnecessary for a storekeeper to keep a stock of different signs on hand as any desired sign 40 may be made up very quickly with the least possible effort. By making the outer mask plate 17 of dark or colored material and the reflecting plates 18 of bright reflecting material, the desired letters or characters will be clearly outlined 45 and shown either by day or by night and pleasing color combinations may be obtained by varying the colors of the plates and reflectors.

50 It is obvious that various other changes may be made in the construction, combination and arrangement of the several parts without departing from the spirit and scope of the invention.

I claim:

55 1. A double faced sign comprising a frame having an opening with a fixed flange projecting inwardly at one side thereof, a plurality of sign characters adapted to be interchangeably seated

in the opening against the flange and in layers to face reversely at opposite sides of the frame, a bendable rim portion at the other side of the frame around the opening deflectable inwardly against the edges of characters seated within the opening at that side for holding them against the characters at the other side and against the fixed flange and the outer faces of the characters being freely visible from opposite sides of the frame. 10

2. A double faced sign comprising a frame with an opening having an inwardly extending flange at one side of the frame, a plurality of sign characters adjustable in the opening and facing reversely at opposite sides, a reflector 15 interposed between sign characters at opposite sides of the frame, and a bendable rim portion at the other side of the frame portion surrounding the opening and bendably offset inwardly against the edges of the sign characters for 20 holding them and the reflector together against the flange and within the opening.

3. A double faced changeable sign comprising a frame having an opening with a fixed inward flange around the opening at one side of the frame, character forming masks adapted to be seated in the opening at both sides of the frame, a double reflector interposed between masks visible from opposite sides of the frame, and a bendable rim at the other side of the opening 25 deflected against the edges of the character masks to bind them together against the flange in the opening with the reflector therebetween so that different characters will be presented at 30 opposite sides of the frame utilizing the same 35 reflector.

4. A sign comprising a soft metal frame having an opening with an inwardly extending flange at one side and a thin marginal rim extending around the opening at the other side of the 40 frame, means at one side of the frame for supporting it in upright position so that both sides of the frame are visible, a plurality of sign character masks insertable in the opening to face oppositely at opposite sides of the sign, a reflector between 45 the character masks at opposite sides of the sign and visible through the openings in the masks, and the rim being deflectable inwardly to engage the edges of the character masks for binding them and the reflector together in the opening and releasably holding them against the flange at the other side of the frame, the rim also being deflectable outwardly to release the edges of the character masks for replacing and interchanging them. 50
